UNITED STATES PATENT OFFICE.

CLIFFORD V. MILLIGAN, OF HOUSTON, TEXAS.

HAT-BLOCKER.

1,264,323.

Specification of Letters Patent. Patented Apr. 30, 1918.

Application filed April 16, 1917. Serial No. 162,444.

To all whom it may concern:

Be it known that I, CLIFFORD V. MILLIGAN, a citizen of the United States, residing at Houston, in the county of Harris and State 5 of Texas, have invented certain new and useful Improvements in Hat-Blockers, of which the following is a specification.

This invention relates to new and useful improvements in a hat blocker.

10 The object of the invention is to provide a device of the character described whereby hats in the rough may be blocked or formed into any desirable shape and size in one operation.

15 Another feature of the invention resides in the provision of a machine of the character described which may be readily adjusted so as to form a rough hat into any desirable shape and to give it the required size.

20 A further feature of the invention resides in the provision of a comparatively simple machine which may be cheaply constructed and easily and quickly operated to accomplish the purposes for which it is designed.

25 With the above and other objects in view, the invention has particular relation to certain novel features of construction, operation and arrangement of parts, an example of which is given in this specification and 30 illustrated in the accompanying drawings wherein:

Figure 1 is a fragmentary transverse sectional view of the device showing the hat therein, in position to be blocked.

35 Fig. 2 is a fragmentary transverse sectional view showing the hat blocked.

Fig. 3 shows a bottom plan view of the flange, showing the sizer therein.

40 Fig. 4 is a side view of the complete machine in position ready for operation.

Fig. 5 is a side view of the machine in operation.

Referring now more particularly to the drawings wherein like numerals of reference 45 designate similar parts in each of the figures, the numeral 1 refers to a hollow flange stand within the wall of which is the annular steam chamber 2 communicating with which is the steam inlet pipe 3 and the steam 50 outlet pipe 4. The lower part of this flange stand has the annular flange 5 integral therewith. The numeral 6 refers to a crown block having a central chamber 7 communicating with which are the inlet and outlet 55 steam pipes 8 and 9, the crown of said block

being oval and provided with a plurality of perforations 10.

The working parts of the machine are mounted upon a table 11. The crown block 6 is fixed to the upper end of the externally threaded shaft 12. This shaft is threaded through a bearing 13, carried by the table and is manipulated by a hand wheel 14 fixed to the lower end thereof. Extending upwardly from the back part of the table is an 65 arm 15 pivoted to which is the lever 16 whose forward end is attached to and supports the flange stand. The other end of this lever is operatively connected with a foot pedal 17 through any suitable mechanism whereby 70 the lever may be manipulated to lift the flange stand into the position shown in Fig. 4, or to lower it into operative position as shown in Fig. 5. This mechanism for manipulating said lever is in common use in 75 steam clothes pressing machines and it is not thought necessary to describe same in detail.

In the operation of blocking a hat, the brim 18 is fitted over the crown block 6, said block 80 gradually flaring downwardly and forming a support for said brim. The sizer 19 is then fitted over the crown block and adjusted to the desired size through the medium of a turn buckle 20. The rough hat 21, to be 85 formed is then fitted over the crown block, the brim of the hat resting upon the brim 18 of the block. There is interposed, however, between the block 6 and the crown of the hat, a thick padding 22 of felt or other soft 90 material. By a suitable manipulation of the foot pedal 17, the forward end of the lever 16 is lowered, bringing the flange 5 down on to the hat brim and clamping it between said flange and brim 18 as shown in Figs. 1 and 95 5, the flange stand 1 at the same time fitting closely around the crown of the hat.

For the purpose of giving the top of the crown the desired shape, a topper 23 is provided. This topper is carried by the lower 100 end of the screw shaft 24, said shaft being manipulated by the hand wheel 25 and being threaded through the internally threaded bearing 26 which is fixed in position above the stand 1 by means of the standards 27, 27. 105 The shaft 24 has a swiveling connection with the topper 23 so as to rotate independently thereof. By the rotation of the shaft 24, the topper may be forced downwardly against the top of the crown and said crown given 110

any desirable shape in accordance with the contour of the under side of the topper. When the topper is screwed down into position against the crown of the hat, steam is admitted into the chamber 2 through the pipe 3 and passes thence through the orifices 28 through the inner wall of the flange stand and out through the pipe 4. At the same time steam is admitted through the pipe 8 into the chamber 7 and passes thence through the orifices 10 and out through the outlet pipe 9. The hot steam thus passes through the fabric and makes the same soft and pliable so that it will receive the desired form while being blocked. These steam pipes are controlled by suitable foot pedals in the manner now in common use in steam pressing machines.

While this machine has been designed particularly for blocking hats, in the rough, it may also be used for reblocking and reforming used hats.

What I claim is:

1. A hat blocker including a block, a brim carried thereby, a flange stand having an annular flange adapted to fit over said block to give form to the hat on said block, said block and stand being provided with conduits to permit the passage of steam through said hat.

2. A hat blocker including a block, a detachable brim carried thereby, a sizer surrounding the block adjacent the brim, a flange stand adapted to fit over the block and a flange carried by said stand and opposing and coöperating with said brim.

3. A hat blocker including a hollow block for forming a hat crown provided with perforations, a detachable brim carried thereby, a sizer surrounding the block adjacent the brim, a flange stand provided with perforations adapted to fit over the hat crown, a flange carried by said stand and adapted to coöperate with the brim to clamp the hat brim between said flange and brim, and conduits through which steam may be passed through said perforations.

4. A hat blocker including a block for forming a hat crown, a detachable brim carried thereby, a sizer surrounding the block adjacent the brim, a flange stand adapted to fit over the hat crown, a flange carried by said stand and adapted to coöperate with the brim to clamp the hat brim between said flange and brim, and an adjustable topper adapted to fit into the flange stand against the hat crown.

5. A hat blocker including a hollow block whose crown is provided with a plurality of steam passageways therefor, a steam inlet and a steam outlet communicating with the interior of the block, a detachable brim carried by the block, a flange stand

adapted to fit over said block the lower part of said stand being formed into a flange 65 which coöperates with said brim to form the hat brim therebetween, a topper adapted to rest against and give form to the crown of the hat and means for adjusting said topper.

6. A hat blocker including a hollow block whose crown is provided with a plurality of steam passageways, an adjustable support whereon said block is mounted, a steam inlet and a steam outlet communicating with the interior of said block, a detachable brim carried by the block, a sizer surrounding the block adjacent the brim, a flange stand adapted to fit over the hat being formed on said block, said stand being formed into a flange adjacent the brim and which coöperates with said brim to form the hat brim, said stand having an annular internal steam chamber and the interior wall thereof being provided with a plurality of steam passageways, a steam inlet and outlet communicating with said chamber and a topper adapted to operate against the hat crown to give form thereto.

7. A hat blocker including a hollow block 90 whose crown is provided with a plurality of steam passageways, a support for said block, a steam inlet and a steam outlet communicating with the interior of the block, a brim carried by the block, a sizer surrounding the block adjacent the brim, a flange stand adapted to fit over the hat being formed on said block, said stand being formed into a flange adjacent the brim which coöperates with said brim, said stand 100 having an internal steam chamber and the inner wall thereof being provided with a plurality of steam passageways, an inlet and an outlet for said chamber, and means for manipulating the stand relative to the 105 block.

8. A hat blocker including a block for forming a hat crown, a brim carried thereby, a sizer surrounding the block, a flange stand adapted to fit over the hat crown, a 110 flange carried by said stand and adapted to operate with the brim to clamp the hat brim between said flange and brim, said block and stand being provided with conduits to permit the passage of steam through 115 said hat, an adjustable topper adapted to fit into the flange stand against the hat crown to give form to said crown.

In testimony whereof I have signed my name to this specification in the presence 120 of two subscribing witnesses.

CLIFFORD V. MILLIGAN.
